UNITED STATES PATENT OFFICE.

JULIUS MAIER, OF STUTTGART, GERMANY.

CHANGEABLE-PICTURE ADVERTISING APPARATUS.

Application filed June 16, 1925, Serial No. 37,568, and in Germany May 7, 1925.

Advertising apparatus is already known in which a series of changing pictures is produced and in which the separate or individual pictures are divided into strips and so secured on frames that they press through one another and by changing opposite displacement of the picture frames one or the other alternately appears, whilst the others remain covered.

All these apparatus have, however, the disadvantage that they work very inefficiently and that they only permit of the production of a very limited number of pictures heretofore at most three. This inconvenience originates from the fact that the driving arrangements in apparatus of this class heretofore extant were completely unsuitable. The production of the pictures in the aforesaid apparatus effected by a lifting or raising disc which is provided on its periphery with projecting lugs and effects a periodic rotational movement at intervals. It follows that the production of the pictures takes place at intervals and therefore at the change two pictures always appear partially overlapping one another and the lifting or raising disc working without energy is often unable to execute the displacement against the friction of the frame. The arrangement of the projecting lugs on the periphery of the lifting or raising disc limits, however, the number of the movable picture frames to two at the most as further levers cannot be used without mutually hindering each other.

A further disadvantage of the hitherto known driving arrangements in such advertising apparatus is that the movable frames sliding on one another and pushing on one another exert a wearing action on each other by friction so that series of pictures become disarranged. For example, instead of the second picture there simultaneously appears a third picture. All these disadvantages are avoided by the advertising apparatus according to the present invention which possesses such a form that any suitable number of changeable pictures can be provided for exhibition.

The present invention effects the movement of the frames by a uniformly rotating disc which is provided with striking pins of different lengths extending in an axial direction and increasing in length in the opposite direction to that of the direction of rotation. In the path of these striking pins

is arranged a series of levers lying behind one another and projecting at different distances from the disc which levers are rocked in succession by the relevant striking pins and are in engagement with slide rails lying in the plane of the picture frame, the said slide rails being connected by means of a link with a frame and adapted to be moved in the direction of displacement of the frame. In this manner it is possible to render any suitable number of picture frames movable, the arrangement thus resulting in that the entire number of pictures can be fully changed by the insertion or removal of the frames and the increase or decrease of the striking pins arranged in the direction of rotation of the driving disc, the said pins being of increasing lengths.

A further improvement of the driving arrangement consists in that the same is provided with a catch arrangement which retains the frames in the direction in which they shall be individually moved and which are only released at the beginning of the systematic movement of the respective picture frame. The catch arrangement consists conveniently of a pawl of bell crank formation linked to the slide rail one arm of the said pawl being supported against a fixed stop whilst the other arm of the pawl projects into the path of the respective slide rail actuating lever so that the lever moved forward by the driving disc at first lifts the pawl over the striking pin and then effects only the displacement of the slide rail with the frame.

A further improvement of the invention consists in that the apparatus has a lighting arrangement provided at the front of the apparatus. In picture advertising apparatus known hitherto the lighting arrangement was arranged behind the pictures and this was disadvantageous from the point of view that the pictures in consequence of the picture strips covering one another appeared likewise striped. They were only faintly illuminated and this had the effect of altering or disturbing the impression of the respective pictures more particularly by reason of the light rays falling through the spaces between the picture strips. According to the present invention the lighting is effected by tubular lamps which are secured on the inside of the front window frame of the casing containing the mechanism, the said tubular lamps being covered above and

below. The tubular lamps can be readily removed and replaced without disturbing the wiring connections. In this manner an efficient and uniform lighting of the picture surface is obtained all shadows on the picture strips being avoided.

In order that the invention may be clearly understood and readily carried into practice, reference is made to the accompanying drawing which shows a constructional form in accordance with the present invention for producing five pictures.

Figure 1 shows a back view of an advertising apparatus in accordance with the present invention.

Figure 2 is a front view of the same showing the window frame partly broken away.

Figure 3 is a vertical cross section of the apparatus.

Figure 4 shows a side view of the driving arrangement.

Figure 5 is a driving arrangement looking on the driving disc.

Figure 6 is a plan of Figure 5.

Figures 7 to 11 show successive positions of the picture frame.

The pictures to be produced are in a manner known per se divided into small pictures strips a and secured on frames b one of which is fixed, the others being displaceable. The fixed frame is indicated at b^0 and the movable frames at b' , b^2 , b^3 , b^4 , the associated parts bearing the same references. a^0 indicates the picture strips of the stationary frame and a' , a^2 , a^3 , a^4 indicate the picture strips of the movable frames respectively. The movable frames b' to b^4 whose picture strips a' to a^4 press through one another and mutually overlap are guided and supported by means of straps or slide members c' , c^2 , c^3 , c^4 on a cross bar d of the fixed frame a and extending across their planes and lying in the same plane as the cross bar d so that the whole frame can be inserted as a composite piece into a casing e . The casing e is provided on its front side with a window through which the pictures are seen and carries the lighting arrangement and the driving mechanism for the movable frame.

The driving arrangement especially consists in a driving disc f to which a constant uniform rotational movement may be imparted by means of a worm g and gearing h , the latter being driven by a cord or belt pulley i which may receive its motion from an electric motor M . Striking pins k' , k^2 , k^3 , k^4 are provided on the driving disc f and are removably fixed thereto, which pins are disposed parallel to the axis l and extend over the plane of rotation of the driving disc, the said pins being of different lengths so that the pin k' actuating the first frame b' is the shortest, the other pins being of successive increasing lengths. These striking pins may be arranged concentrically round

a circle or the said striking pins of any desired number may be arranged concentrically but on circles of different diameters on the driving disc f .

Lugs m' , m^2 , m^3 , m^4 provided on levers n' , n^2 , n^3 , n^4 respectively are arranged in the path of the ends of the striking pins k' to k^4 which levers are rotatably supported on a common shaft o supported by the frame p of the driving arrangement. The levers n' to n^4 engage with slide rails q' , q^2 , q^3 , q^4 which are provided with recesses r' for the heads s' of the levers n' to n^4 . One end t' of a bell crank lever u' projects into the recess in each slide rail, there being a bell crank lever for each slide rail. The upper end v of the bell crank levers in the position of rest engage behind a fixed lug or stop w and being supported thereagainst. On the end of each slide rail q' to q^4 is a forked member x' , x^2 , x^3 , x^4 respectively which engages a projection y' , y^2 , y^3 , y^4 respectively which is rigidly connected with the respective one of the movable frames b' to b^4 .

The movement of the picture frame takes place in such manner that the frames b' to b^4 lying behind the fixed frame b^0 (see Figure 7) are displaced serially in the same direction so that their picture strips a push themselves in front of the picture strips of the preceding frame. The individual frames are displaced by the frame a' of the associated striking pin k' on the driving disc f against the lug m' of the lever extending under the shaft o . The result is a rocking of the lever n' the head s' of which engages in the recess r' of the slide rail q' and at first bears against the lower lever t' of the pawl n' in order to rock its axis so that the lever v' is raised over the pin or stop w and the slide rail q' is freed. At this moment the head s' strikes against the wall of the recess r' and displaces the slide rail q' as shown in dotted lines in Figure 5. The fork x' is thus actuated and in its movement it takes the pin y' with it and therefore the frame b' and thus causes the appearance of the picture secured to the frame b' , Figure 8, wherein the picture of the fixed frame was hitherto visible, Figure 7. The movement of other picture frames takes place in a similar manner so that these appear in succession according to the manner shown in Figures 7 to 11.

Should all the movable frames b' to b^4 be displaced and their pictures exhibited, Figure 9, the movable frames b' to b^4 inclusive are simultaneously restored again to their position behind the fixed or stationary frame b^0 . This is effected by a further pin z which is positioned on a larger diameter than the other striking pins k' to k^4 and strikes against a lateral projection j or lug on the lever n' lying in its path, the said projection j being disposed over the axis o .

The lever n' is therefore rocked in the opposite direction so that the frame b' is moved thereby to its original position. As the slide-members c^1 to c^4 , which all slide on the cross-bar d of the stationary fixed frame b^0 , all lie in the same plane and one behind the other, the movement of the frame b^1 , or its slide-member c^1 , respectively, will cause all the other slide-members c^2 to c^4 10 and their frames b^2 to b^4 to move in the same direction by pushing them out of its path to their original position. In this manner all movable frames b^1 to b^4 are brought to their original positions at the 15 same time.

The casing e is provided on the front side with a window z or opening (Figure 2) which may be glazed or closed by a sheet of clear transparent material and the 20 pictures appear in the frame 1 thereof, Figure 2. Behind the upper and the lower window frame guides is arranged a tubular electric lamp 2, which receives its current through resilient slide-contacts e . By 25 this arrangement it is possible to enclose the lighting arrangement together with the window z in the casing without disturbing or disconnecting the wiring connections or unscrewing or removing the lamps. The 30 opening in the casing is thus quite free and the picture frames can readily be removed as a composite or single unit.

What I claim is:—

1. Advertising device for producing periodically changing pictures, comprising, a plurality of parallel positioned relatively movable, frames, overlapping image strips attached to the frames, actuating slide rails, one for each frame, positioned parallel to 40 each other, pivoted levers, one for each slide rail, for moving the slide rails, the levers being pivoted on a common axis, positioned to swing parallel to the plane of the frames, and placed one behind the other in the direction of their common axis, a projection on each lever, a disc, means to uniformly drive the disc, and removable and interchangeable pins carried by and projecting from the disc, the lever projections extending into the paths of the pins.

2. Advertising device for producing periodically changing pictures, comprising a plurality of parallel positioned, relatively movable, frames, overlapping image strips attached to the frames, actuating slide rails, one for each frame, positioned parallel to each other, pivoted levers, one for each slide rail, for moving the slide rails, the levers being pivoted on a common axis, positioned 50 to swing parallel to the plane of the frames, and placed one behind the other in the direction of their common axis, a projection on each lever, a disc, means to uniformly drive the disc, and removable and interchangeable pins carried by and projecting

from the disc, the lever projections extending into the paths of the pins, the lengths of the projecting pins varying and increasing in the direction opposite to that of the rotation of the disc, so as to successively 70 engage with and actuate the pivoted levers.

3. Advertising device for producing periodically changing pictures, comprising, a plurality of parallel positioned, relatively movable, frames, overlapping image strips 75 attached to the frames, actuating slide rails, one for each frame, positioned parallel to each other, pivoted levers, one for each slide rail, for moving the slide rails, the levers being pivoted on a common axis, positioned to swing parallel to the plane of the frames, and placed one behind the other in the direction of their common axis, a projection on each lever, a disc, means to uniformly drive the disc, and removable and interchangeable pins carried by and projecting from the disc, the lever projections extending into the paths of the pins, and a pawl for retaining each frame in fixed position until released by movement of the corresponding 85 pivoted lever.

4. Advertising device for producing periodically changing pictures, comprising, a plurality of parallel positioned, relatively movable, frames, overlapping image strips 90 attached to the frames, actuating slide rails, one for each frame, positioned parallel to each other, pivoted levers, one for each slide rail, for moving the slide rails, the levers being pivoted on a common axis, positioned to swing parallel to the plane of the frames, and placed one behind the other in the direction of their common axis, a projection on each lever, a disc, means to uniformly drive the disc, and removable and interchangeable pins carried by and projecting from the disc, the lever projections extending into the paths of the pins, the lengths of the projecting pins varying and increasing in the direction opposite to that of the rotation of the 95 disc, so as to successively engage with and actuate the pivoted levers, and a pawl for retaining each frame in fixed position until released by movement of the corresponding 100 pivoted lever.

5. Advertising device for producing periodically changing pictures, comprising, a plurality of parallel positioned, relatively movable, frames, overlapping image strips 105 attached to the frames, actuating slide rails, one for each frame, positioned parallel to each other, pivoted levers, one for each slide rail, for moving the slide rails, the levers being pivoted on a common axis, positioned to swing parallel to the plane of the frames, and placed one behind the other in the direction of their common axis, a projection on each lever, a disc, means to uniformly drive the disc, and removable and interchangeable pins carried by and projecting 110

from the disc, the lever projections extending into the paths of the pins, and a pawl for retaining each frame in fixed position until released by movement of the corresponding pivoted lever, each pawl comprising a pivoted angle lever, an abutment against which one arm of the angle lever normally rests, the other arm of the angle lever being positioned in the path of motion of the corresponding pivoted lever.

6. Advertising device for producing periodically changing pictures, comprising, a plurality of parallel positioned relatively movable, frames, overlapping image strips attached to the frames, actuating slide rails, one for each frame, positioned parallel to each other, pivoted levers, one for each slide rail, for moving the slide rails, the levers being pivoted on a common axis, positioned to swing parallel to the plane of the frames, and placed one behind the other in the direction of their common axis, a projection on each lever, a disc, means to uniformly drive the disc, and removable and interchangeable pins carried by and projecting from the disc, the lever projections extending into the paths of the pins, the lengths of the projecting pins varying and increasing in the direction opposite to that of the rotation of the disc, so as to successively engage with and actuate the pivoted levers, and a pawl for retaining each frame in fixed position until released by movement of the corresponding pivoted lever, each pawl comprising a pivoted angle lever, an abutment against which one arm of the angle lever normally rests, the other arm of the angle lever being positioned in the path of motion of the corresponding pivoted lever.

7. Advertising device for producing periodically changing pictures, comprising, a plurality of parallel positioned, relatively movable, frames, overlapping image strips attached to the frames, actuating slide rails, one for each frame, positioned parallel to each other, pivoted levers, one for each slide rail, for moving the slide rails, the levers being pivoted on a common axis, positioned to swing parallel to the plane of the frames, and placed one behind the other in the direction of their common axis, a projection on

each lever, a disc, means to uniformly drive the disc, and removable and interchangeable pins carried by and projecting from the disc, the lever projections extending into the paths of the pins, a return lug on the disc, a lateral projection on the pivoted lever nearest the disc and above the pivot axis of the lever and in the path of the return lug, and cross bars for slidably guiding the frames, whereby movement of the return lug operates to cause return movements of the frames.

8. Advertising device for producing periodically changing pictures, comprising, a plurality of parallel positioned relatively movable, frames, overlapping image strips attached to the frames, actuating slide rails, one for each frame, positioned parallel to each other, pivoted levers, one for each slide rail, for moving the slide rails, the levers being pivoted on a common axis, positioned to swing parallel to the plane of the frames, and placed one behind the other in the direction of their common axis, a projection on each lever, a disc, means to uniformly drive the disc, and removable and interchangeable pins carried by and projecting from the disc, the lever projections extending into the paths of the pins, the lengths of the projecting pins varying and increasing in the direction opposite to that of the rotation of the disc, so as to successively engage with and actuate the pivoted levers, and a pawl for retaining each frame in fixed position until released by movement of the corresponding pivoted lever, each pawl comprising a pivoted angle lever, an abutment against which one arm of the angle lever normally rests, the other arm of the angle lever being positioned in the path of motion of the corresponding pivoted lever, a return lug on the disc, a lateral projection on the pivoted lever nearest the disc and above the pivot axis of the lever and in the path of the return lug, and cross bars for slidably guiding the frames, whereby movement of the return lug operates to cause return movements of the frames.

In testimony whereof I affix my signature.

JULIUS MAIER.
